UNITED STATES PATENT OFFICE.

ALFRED COHN, OF MILWAUKEE, WISCONSIN.

DESIGN FOR A KNITTED CAP.

Application filed January 2, 1923. Serial No. 4,799. Term of patent 3½ years.

To all whom it may concern:

Be it known that I, ALFRED COHN, a citizen of the United States, residing at Milwaukee, in the county of Milwaukee and State of Wisconsin, have invented a new, original, and ornamental Design for Knitted Caps, of which the following is a specification, reference being had to the accompanying drawing, forming part thereof.

I claim:

The ornamental design for a knitted cap, as shown.

ALFRED COHN.
